UNITED STATES PATENT OFFICE.

JOHN DAILEY, OF VAN WERT, OHIO.

FLOOD-GATE.

SPECIFICATION forming part of Letters Patent No. 340,293, dated April 20, 1886.

Application filed January 26, 1886. Serial No. 189,877. (No model.)

To all whom it may concern:

Be it known that I, JOHN DAILEY, of Van Wert, in the county of Van Wert and State of Ohio, have invented a new and Improved 5 Flood-Gate, of which the following is a full, clear, and exact description.

My invention relates to the construction of a gate which will prevent animals from passing up or down the stream, but which is so 10 arranged that when struck by any heavy débris carried by the stream it will swing upon its connections and be automatically raised to a position such as will allow the débris to pass on down the stream, the said gate being so 15 mounted that it may be raised quite a distance above the bed of the stream at times when there is danger of injury from ice, &c.

Reference is to be had to the accompanying drawings, forming a part of this specification, in 20 which similar letters of reference indicate corresponding parts in all the figures.

Figure 1 is a side view of the gate and connections, certain parts being shown in section to disclose the construction, and the gate being shown in its lower position. Fig. 2 is a cross-sectional view of the gate, and Fig. 3 illustrates the position of the gate when raised above the stream.

In building such a gate as is illustrated in the 30 drawings above referred to, I place two posts, A A', in the position indicated—that is, one post upon each bank of the stream across which the gate is to be swung. These posts are each recessed at their upper ends, as shown 35 at a, and in the recesses so formed I mount sheaves b b, over which sheaves I carry ropes c c, fixed to the upper part of the gate B, said gate being formed to the approximate contour of the bank of the stream. The other ends 40 of the ropes c are fixed to plates d, which are borne upon by spiral springs e, that are coiled about vertical standards f, fixed in the recesses formed in the outer faces of the posts A A'. These standards f are longitudinally slotted, 45 as shown at g, and formed with an upper central aperture, h, through which the ropes c are passed, so that they may be carried down to connect with the plates d, which are mounted in the slots g. From this construction it will 50 be understood that when the springs e are free to act they will force the plates d downward to the position shown in Fig. 3, and thus raise

the gate above the surface of the stream; but in order that the gate may be held in its lowered position, as shown in Fig. 1, I provide 55 each post with a stop, C, said stops being fixed to the inner face of the post. These stops C are T-shaped, having a horizontal and a perpendicular bearing-surface, the perpendicular bearing-surface being upon the downwardly-extending lug k, which is toward the upstream side of the post.

In order that the gate may be depressed, to be brought into engagement with the stops C C, I connect a lever, D, with one of the side 65 posts, A or A', said lever being preferably mounted in a stirrup-loop, l, carried by an arm, E, that is fixed to the supporting-post. The extending end of the lever D is loosely connected to the upper bar of the gate B, so 70 that by lifting the shore-arm of the lever the gate will be carried down below the horizontal face of the stop, and then if said arm of the lever is carried downstream the gate will be carried upstream and beneath the stops, being 75 brought against the lugs k, which define the position of the upper bar of the gate. The downstream corners of the gate are cut away or rounded off, as shown at i i, so that as the lower part of the gate is carried forward in 80 the direction of the arrows in Fig. 2 the gate will slightly rock upon the stops, but when the force of the current subsides will return to its normal vertical position. If any heavy débris should be thrown against the upstream 85 face of the gate, it would be carried free of the stops C, and the springs e would immediately act to draw the gate to the position shown in Fig. 3, thus preventing it from receiving serious injury.

One very material advantage arising from my improved form of gate is that as the winter months approach the gate may be freed from engagement with the stops C and raised above the surface of the stream, where it may be left 95 during the winter months, and thus be unexposed to the danger arising from the breaking up of the stream in the spring.

Having thus fully described my invention, what I claim as new, and desire to secure by 100 Letters Patent, is—

1. The combination, in a flood-gate, of the posts provided with stops, a gate suspended from the posts and resting against the under

faces of said stops, and means for raising the gate when forced away from the stops, substantially as set forth.

2. The combination, with the posts provided with stops on their adjacent faces, the stops each having a horizontal and a perpendicular bearing-surface, of a gate suspended from the posts, with its upstream corners resting within the angles of the stops, and means for raising the gate when forced away from the stops, substantially as set forth.

3. The combination, with the posts provided with J -shaped stops facing downstream, of a gate bearing at its corners in the angles of the stops, a lever pivoted to one post and to the central part of the gate, and devices for raising the gate when forced away from the stops, substantially as set forth.

4. The combination of the posts provided with sheaves at their upper ends and J -shaped stops on their adjacent faces, of the gate bear-

ing at its upper corners in the angles of the stops, ropes connected to the gate and passed over the sheaves, and springs acting on the opposite ends of the cords to pull them down, substantially as set forth.

5. The combination, with the posts having sheaves on their upper ends and stops on their inner adjacent faces, of a gate resting at the ends of its upper edge against said stops, ropes connected to said ends and passed over the sheaves, slotted standards on the outer faces of the posts, between which the free ends of the ropes pass, plates on the ends of the ropes within the slots, and springs surrounding said standards and bearing on the plates to force the ropes down, and thereby raise the gate when forced from the stops, substantially as set forth.

JOHN DAILEY.
